UNITED STATES PATENT OFFICE.

JOSEPH CORBETT, OF NEW YORK, N. Y., ASSIGNOR TO THE AUTOMATIC SELLING MACHINE COMPANY, OF SAME PLACE.

VENDING-MACHINE.

SPECIFICATION forming part of Letters Patent No. 416,828, dated December 10, 1889.

Application filed November 18, 1887. Renewed August 27, 1889. Serial No. 322,087. (No model.)

To all whom it may concern.

Be it known that I, JOSEPH CORBETT, of the city, county, and State of New York, have invented a new and Improved Coin-Controlled Vending-Machine, of which the following is a full, clear, and exact description.

This invention relates to machines that are arranged to automatically deliver articles or packages of goods upon the deposit of a coin of predetermined value, the main objects of the invention being to provide for the positive locking of the delivery apparatus and to prevent the unlocking thereof except upon the deposit of a coin of the prescribed value; and to these ends the invention consists, essentially, of a locking-bar, a lug connected to a slide, and a coin-delivery apparatus by which the coin is so guided as to move the locking-bar to a position such that the lug may pass its forward edge, many other objects, however, being sought for and attained by the novel construction of parts and combinations of elements to be hereinafter described, and specifically pointed out in the claims.

Reference is to be had to the accompanying drawings, forming a part of this specification, in which similar figures and letters of reference indicate corresponding parts in all the views.

Figure 1 is a central sectional elevation of my improved automatic selling-machine. Fig. 2 is a sectional plan view taken upon a line corresponding with that of the line *xx* of Fig. 1. Fig. 3 is a plan view of one of the tumblers, the coin-guiding way and the fence arranged in connection therewith being shown in section. Fig. 4 is a sectional elevation taken on the broken line *yy* of Fig. 1. Fig. 5 is a sectional detail view taken on the broken line *zz* of Fig. 1. Fig. 6 is a sectional detail view taken on line *ww* of Fig. 4. Fig. 7 is a front elevation of the machine, parts being broken away. Fig. 8 is a cross-sectional view taken on line *xx* of Fig. 7. Fig. 9 is a sectional detail view taken on line *yy* of Fig. 7. Fig. 10 is a sectional view taken on line *zz* of Fig. 7, and Fig. 11 is a sectional detail view on line *ww* of Fig. 7.

In the drawings above referred to I have represented an apparatus designed to deliver two species of article; but it will of course be

understood that a machine might be made to deliver but a single species or several species.

In the form illustrated, 10 represents an inclosing-case, the lower portion of which is closed by a door 11, that is hinged to the base of the case, this door being provided with a lock, of which the bolt 12 is thrown upward to engage with its keeper. The upper part of the front of the case is made up of two glass plates 13 and a mullion 15, the outer edges of the plates being held in grooves formed in the inner faces of the side walls 14, while the inner edges of the plates are held in grooves formed in the mullion 15, as is probably best shown in Fig. 11. The top of the case is formed with slots 16, located directly above the upper ends of the glass plates; and it is through these slots that the plates are passed when the supply of goods is to be introduced; but in order to prevent the raising of the plates by unauthorized persons I mount a curved locking-plate 17 just within the front of the case, said plate being formed with an eye 18, through which there is passed a rod 19, the ends of which rest in apertures formed in the side walls 14. The forward edge of the plate 17 is bent, as shown at 2 in Fig. 8, so as to extend over the upper edge of the glass plates when the upper portion of the plate is swung forward.

To the plate 17, I connect a rod 20, which extends downward in a rabbet formed at one of the inner corners of the mullion 15, the rod being held by guides 21, as indicated in Fig. 11, the lower end of the rod resting upon the bolt 12, the arrangement being such that when the bolt is thrown upward to lock the door 11 the rod will be raised and the bent edge 2 of the plate 17 will be thrown over the upper edges of the plates 13, thus preventing any upward movement of the plates; but when the bolt 12 is thrown to unlock the door the forward edge of the plate 17 will be carried free of the upper edges of the plates 13, and they may then be moved upward through the slots 16.

Just above the upper edge of the door 11, I mount a base-plate 22, in which there is formed a transverse slot 23, and at each side of this slot I secure upwardly-extending walls 24 and 25, that are connected by a central

bridge or partition 26, which bridge, however, does not extend to the upper edges of the walls. The recesses between the walls at each side of the bridge 26 form coin-receptacles *e* and *f*. At each end of the walls I mount slides 27, said slides being guided in apertures formed through the front wall of the case just above the door 11 and in other apertures formed in a flange 28, which extends upward from the rear edge of the base-plate 22, a similar flange or plate 29 being secured to the inner face of the front of the case and to the base-plate 22, the flanges 28 and 29 being preferably made integral with the plate 22. In order that the slides may be normally held extended, as illustrated in Figs. 1 and 2, I arrange a spiral spring 30 in connection with each slide, said springs being coiled about forwardly-extending bars 31, which pass through apertured lugs 32, that are secured to the slides, one end of each spring abutting against the forward face of the flange 28, while the other end of each spring abuts against its lug 32. The slides 27 are provided or formed with lugs 3, and to the rear of these lugs I mount locking-bars 34, which said locking-bars are preferably formed with slots 4 and with serrated forward edges 5, the slots of the locking-bars being normally held out of register with the lugs 3 by springs 35, which are connected to the locking-bars and bear against pins 6, that extend upward from the base-plate 22; or any other form of spring than that illustrated and described could be employed to throw the locking-bars inward within slots 7, that are formed in the ends of the walls 24 and 25. To the inner faces of the slides I secure horizontal plates 36, that are slotted transversely to form cutting-edges 37 and arms 38, which arms extend inward over the space between the walls 24 and 25. From the arms 38 there are downwardly-extending arms 40, the lower ends of which are bent forward to form fingers 8, that pass through the lower portions of the walls 24 and 25 and over the slot 23, that is formed in the base-plate 22.

In order that a coin of the prescribed value may be delivered to operate in connection with the apparatus hereinbefore described, I secure to the outer face of the mullion 15 a tube 41, the lower end of which is open, while the upper end is closed, except for a slot 42, which is only just large enough to permit of the introduction of the coin. Extending upward within this tube 41, and connected to the under side of the top thereof, is a chute 43, of which the portion that is within the tube is open at the under side, except for side flanges 44, which approach each other to an extent sufficient to support and hold a coin of the prescribed diameter and value, but which will not support a coin of less diameter than the one in connection with which the machine is to be employed, so that when a coin of smaller diameter is passed through the slot 42 it will drop downward through the tube

41 and onto a receiving-tray 45, located directly beneath the lower open end of the tube. Within the case the chute 43 is provided with side flanges 46, which serve to guide the coin in its downward passage to a tilting plate 47, that is provided with trunnions 48, that rest in bearings formed in side plates 49. This tilting plate 47 carries a counterbalancing-weight 50, which acts to hold the forward end of a curved arm 51 against an upwardly-extending finger 52, that is connected to a spring 53, the purpose of which spring will be herein-after explained. At each side of the upper edge of the plate 47 there are overturned ears 54, the lower corners of which more closely approach the upper face of the plate 47 than do the upper corners, the space between said lower corners 85 and the upper face of the plate being sufficient to just permit a coin of less thickness than that of the coin of prescribed value to pass through and downward between the ears, such coin slipping over the plate 47 and into a hopper 55, which is provided with side flanges 56, passing thence through the hopper, through a slot 57, formed in the base-plate 22, and downward through a chute 58, to be delivered to a tray 59, which is located beneath the door 11; but if a coin of the prescribed value be passed through the slot 42 it will slide downward through the chute 43 and will be caught by the ears 54 of the plate 47 and overbalance the weight 50, tilting the plate 47 to the position in which it is shown in dotted lines in Fig. 1, the lower portion of the chute 43 being cut away, as shown at 60, to provide for this downward passage of the coin.

To insure a discharge of the coin from the ears of the plate 47, I provide an inclined-faced horn 61, which, as the plate 47 tilts downward, passes through a slot or opening *g*, that is formed in the plate 47, and forces the coin from engagement with the tilting plate and into a guiding-chute 62, which delivers the coin so that its lower edge will just enter the space between the walls 24 and 25 above the bridge 26, the coin being supported above the bridge by the arms 38. While in this position, if either of the slides 37 be forced inward against the tension of the springs 30, its arm 38 will be carried from above the space between the walls 24 and 25, and the coin, being thus unsupported at this side, will drop downward between the walls to the position indicated by dotted lines in Fig. 4, and in so falling will move the locking-bar to a position so that its slot will be brought into register with the lug arranged in advance of the locking-bar, thus permitting a further inward movement of the slide, the coin being upheld until the lug has fairly entered the slot of the locking-bar by the finger 8, but dropping through the slot 23 and into the coin-receiving box A after the finger has passed beyond the forward face of the wall 25. When the pressure upon the slide is released, the spring

30 will act to force it forward to its normal position, and the locking-bar will be moved so that its slot will be carried out of register with the lug by the action of the spring 35. 5 It will thus be understood that after a coin has been deposited it will, before one of the slides is moved, rest upon the bridge 26 and the inner edges of the plates 36 of both slides. If then the right-hand slide is pushed in, its 10 plate 36 will be moved so as to uncover the right-hand coin-receptacle, into which the coin will then drop, displacing the right-hand locking-bar and permitting the delivery, on the further inward movement of the slide, of 15 an article contained in the right-hand package-receptacle—that is, as shown in the drawings, a package of chewing-gum will be delivered; but if the left-hand slide be pushed in then in a similar manner a package of 20 cigarettes will be delivered. An intending purchaser will thus obtain the article he desires by operating the slide next adjacent to the name indicating the desired article.

Many forms of delivery mechanism could 25 be employed in connection with the operating mechanism above described. In the drawings I have illustrated two forms of delivery mechanism, the one upon the left consisting of a segmental gear 70, that is pivotally 30 mounted upon a stud 71, said stud extending upward from the base-plate. A sleeve 72, which is rigidly connected to the gear 70, extends downward about the stud 71 and at its lower end carries a pusher-arm 73, which is 35 provided with a plate 74, that extends downward within a package-receptacle 75, the goods to be delivered by the machine being piled one upon the other within this package-receptacle, as is indicated in dotted lines in 40 Figs. 2 and 4. The teeth of the segmental gear 70 engage with apertures formed in the slide 27, the throw of the slide in either direction being limited by spurs 76, that are arranged as shown in Fig. 2. Just above the 45 base-plate 22, I mount a sliding plate 77, which is formed with diagonal slots 78, having extensions 79, that are parallel with the slide 27, the plate being mounted to slide on rods 80. To the slide 27, I secure arms 81, which are 50 provided with downwardly-extending studs 82, that ride in the slots 78. At the rear of the plate 77 there is an outwardly-extending projection 83, the purpose of which will be herein-after described. Just in advance of the 55 lower portion of the package-receptacle 75, I form an opening 84 in the front wall of the case, which opening is normally closed by a shutter 85, that is pivoted to the flange 29 and provided with a finger 86, the inner end of 60 which rides in a slot 87, so shaped that as the slide is forced inward the shutter will be thrown upward to clear the passage through the opening 84.

In this particular delivery mechanism the 65 parts coact as follows: After the locking-bar has been moved to a position so as to permit the slide to be forced inward the arm 73 will

be thrown forward in the direction of the arrow and the lowest package of goods will be carried forward, the shutter 85 at this time 70 rising abruptly to clear the passage for said package, and at the same time the plate 77 will start forward in the direction of its arrow, its projection 83 entering beneath the inner rear corner of the second package of goods—that is, the package of goods the position of which is indicated by the letter *b* in Fig. 4—75 so that as the lever 73 continues to move forward the goods will be forced outward through the opening 84 and onto a receiving-tray 88 80 to a position so that they may be grasped by the purchaser. After the goods have been taken from the tray and the pressure upon the slide has been released the spring 30 will 85 act to return the parts to their normal position, ready for action upon the deposit of another coin.

Upon the right-hand side of the machine the delivery mechanism consists of a slide 90, mounted upon bars 91 and passing outward 90 through an opening in the front wall of the machine to there engage with an automatically-closing shutter 92, which shutter is arranged so that as the slide is forced forward to the position in which it is shown in Fig. 6 it 95 will drop downward, as shown in said figure; but when the slide returns the lower edge 93 of the shutter 92 will strike against the front of the case and the shutter will be returned to the position in which it is shown in Fig. 1. 100 To throw the shutter forward, I provide a lever 95, that is pivotally mounted upon a stud 96 and operated by a lever 97, pivoted upon a stud 98 and provided with a pin which rides in a slot formed in the lever 95. The 105 forward end of the lever 97 rides in a recess 99, formed in the slide 27, so that as the slide is forced inward the lever will be carried in the direction of its arrow.

A shutter 85^a, arranged substantially as is 110 the shutter 85, is mounted as illustrated.

To uphold the column of goods, I provide a presser-foot 100, that is mounted upon a stud 101 and guided so that it will move in a horizontal plane by any proper form of guide. 115 This presser-foot is provided with a toe 102, which normally rests in a slot formed in the slide, so that as the slide is moved inward the presser-foot will be thrown in the direction of its arrow and will be brought to bear against the second package of goods, forcing said package against the outer side guides 103 and thus upholding the column of goods. 120

If desired, the coin-receptacle A might be 125 additionally protected by cleats 104, arranged as illustrated in Figs. 7, 9, and 10.

Although I greatly prefer to employ a slotted locking-bar, still in certain cases I might employ an unslotted locking-bar and force the locking-bar bodily aside from the path of 130 the coin, as will be readily understood; and although I have not illustrated or described any means for insuring a full inward or outward throw of the slides, still it will be under-

stood that the usual form of double-acting pawl might be employed, or that any other proper means for so insuring a full movement in each direction could be used in connection with my apparatus.

5 From the description and drawings it will be noticed that I have provided a somewhat roundabout path for the delivery of the coin to a position to trip the tumbler. This I do to prevent all tampering by means of wires, while a coin attached to a string could be used but once, owing to the fact that as the slides are forced inward the knife-edges 37 would sever the cord, and the coin would drop downward into the coin-receptacle.

10 Should an intending purchaser by accident deposit two coins of the specified value prior to shoving in either slide, it is desirable that the second coin be returned to him, and it is to this end that I provide the spring 53, hereinbefore referred to. This spring is provided with a cam-faced projection 9, which extends into the lower portion of the guiding-chute 62, through a slot formed in the inner side wall of said chute, to a position such that when a coin passes downward within the chute to rest upon the arms 38 it will press the projection toward the rear of the case and will carry the finger 52 in the direction of the arrow shown in connection therewith, and this movement of the finger will tilt the plate 47, so that the lips 54 will be carried below the lower edge of the chute 43, and consequently when the second coin is deposited it will pass over the plate 47 and into the hopper 55, to pass thence to the tray 59.

15 Having thus fully described my invention, I claim as new and desire to secure by Letters Patent—

20 1. In a vending-machine, a coin-receptacle and a swinging locking-bar which normally rests partly within said receptacle and is displaced therefrom upon the contact of a coin entering into said receptacle, in combination with an operating-slide which is normally prevented from effective operation by said locking-bar, said slide having a projecting arm which extends across said coin-receptacle

25 in the path of the coin above said locking-bar, substantially as set forth, whereby the coin cannot displace said locking-bar until said slide is manipulated to move said arm.

30 2. In a vending-machine, a coin-receptacle and a swinging locking-bar, which normally rests partly within said receptacle and is displaced therefrom upon the contact of a coin entering into said receptacle, said locking-bar having a slot therein, in combination with an operating-slide which is normally prevented from being operated by said locking-bar, but which registers with said slot upon the insertion of a coin, substantially as set forth.

35 3. In a vending-machine, a coin-receptacle and a horizontally-swinging locking-bar which normally rests partly within said receptacle and is displaced therefrom upon the

contact of a coin entering in said receptacle, said locking-bar having a longitudinally-extending slot open at the front edge of said locking-bar, in combination with an operating-slide which is normally prevented from effective operation by said locking-bar, said slide having a projecting lug which normally engages said locking-bar, but which registers with said slot when said locking-bar is displaced by the contact of a coin therewith, and said slide having a projecting arm which extends normally across said coin-receptacle in the path of the coin above said locking-bar, substantially as set forth.

4. The combination, with a slide provided with a lug, of a locking-bar arranged in advance of the lug, a coin-receptacle, a spring arranged in connection with the slide, and an arm connected to the slide and provided with a finger which extends beneath the coin-receptacle, all parts coacting as and for the purpose stated.

5. A vending apparatus comprising two slides, each provided with a lug, springs arranged in connection with the slides, locking-bars mounted in the paths of the lugs and provided with springs, coin-receptacles, a bridge or partition between said receptacles, arms connected to the slides and extending over the coin-receptacles, and a single coin-chute leading to said coin-receptacles, as and for the purpose stated.

6. A vending apparatus comprising two slides, each provided with a lug, springs arranged in connection with the slides, locking-bars mounted in the paths of the lugs, coin-receptacles, a bridge or partition between said receptacles, arms connected to the slides and extending over the coin-receptacles, other arms also connected to the slides and provided with fingers which extend below the coin-receptacles, and a single coin-chute leading to said coin-receptacles, as and for the purpose stated.

7. The combination, with a slide, of a spring arranged in connection therewith, a plate connected to the slide and provided with an arm having a cutting-edge, and a coin-receptacle over which the plate-arm extends, as and for the purpose stated.

8. The combination, with a slide, of a spring arranged in connection therewith, a plate connected to the slide and formed with an arm 38 and a cutting-edge 37, an arm 40, extending downward from the arm 38, and provided with a finger 8, which extends beneath the coin-receptacle, all parts coacting as and for the purpose stated.

9. In a vending-machine, a coin-receiving chute, a coin-receptacle, and mechanism actuated by a coin on the deposit thereof into said receptacle, in combination with a tilting plate which receives the coin from said coin-receiving chute and a guide-chute into which the coin is delivered by said tilting plate, which conducts the coin to said coin-receptacle, substantially as set forth.

10. In a vending-machine, a coin-receiving chute and a tilting plate constructed to stop the progress of and be tilted by a coin of the proper thickness, but to permit the onward progress of a coin of a lesser thickness, in combination with a coin-guide chute which receives the proper coin from said plate and conducts the same to the coin-actuated mechanism and a returning-chute which receives 10 coins from said tilting plate of less than the prescribed thickness and returns them to the depositor, substantially as set forth.

11. In a vending-machine, a coin-receiving chute and a tilting plate having overturned ears, the lower corners of which approach the upper surface of said plate to a distance less than the thickness of the prescribed operating-coin, in combination with a coin-guide chute which receives the proper coin from 20 said tilting plate and conducts the same to the coin-actuated mechanism and a returning-chute which receives coins of less than the prescribed thickness and returns them to the depositor, substantially as set forth.

25 12. In a vending-machine, a coin-receiving chute and a tilting plate constituting a continuation of said receiving-chute, said tilting plate having overturned coin-holding ears and having a slot extending longitudinally 30 between said ears, in combination with a coin-guide chute which receives the coin from the tilting plate and conducts it to the coin-actuated mechanism and an inclined-faced horn below said tilting plate and in the path of the 35 slot therein, whereby when said plate is tilted said horn enters said slot and insures the deposit of the coin into the coin-guide chute, substantially as set forth.

13. A vending-machine comprising a single 40 coin-receiving chute, a single tilting plate provided with overturned ears arranged at the bottom of said chute, a single guiding-chute 62 below said tilting plate, coin-receptacles below said guiding-chute, a bridge between 45 said receptacles, slides 27, springs arranged in connection therewith, lugs carried by the slides, locking-bars mounted in advance of the lugs, and arms secured to the slides and extending over the coin-receptacles, substantially as set forth.

50 14. In a vending-machine, the combination, with a coin-receiving chute, of a tilting plate provided with overturned ears mounted at the bottom of the chute and formed with a 55 slot g, an inclined-faced horn 61, arranged to enter the slot g, a receiving-chute, coin-receptacles below said receiving-chute, a bridge between said receptacles, slides 27, springs arranged in connection therewith, lugs carried by the slides, locking-bars mounted in advance of the lugs, and arms secured to the slides and extending over the coin-receptacles, as and for the purpose stated.

60 15. The combination, with a slide and a

means for locking the same, of a plate mounted to slide on ways and formed with slots 78, arms carried by the slide, and studs extending from said arms and entering the slots 78, as and for the purpose stated.

16. The combination, with a slide formed 70 with a rack and a means for locking the slide, of a pivotally-mounted pusher-arm provided with a segmental gear that is engaged by the rack of the slide, substantially as described.

17. In a vending-machine, the combination, 75 with a coin-receiving chute, of a tilting plate provided with overturned ears arranged at the bottom of said chute and formed with a slot g, an inclined-faced horn 61, arranged to enter said slot upon the tilting of the plate, a 80 receiving-chute 62, a spring 53, provided with an inclined-faced projection 9, which enters the lower portion of the receiving-chute, a finger 52, extending upward from the spring 53, an arm 51, connected to the tilting plate 85 and arranged to bear normally against the finger 52, a hopper 55, and a delivery-chute 58, substantially as described.

18. In a vending-machine, a case formed with a slotted top and grooved side walls, a 90 panel sliding in said grooves and through said slot, a door mounted at the bottom of the case, and a lock on said door having a vertically-movable bolt, in combination with a swinging plate mounted on the upper part of 95 the casing and having its upper edge bent to extend over said panel, and a rod connected to said plate and resting on said bolt, substantially as set forth.

19. A vending apparatus comprising a coin-receiving chute, a tilting plate provided with overturned ears arranged at the bottom of said chute and formed with a slot g, an inclined-faced horn 61, arranged to enter said slot upon the tilting of the plate, a receiving-chute 62, a spring 53, provided with an inclined-faced projection 9, which enters the lower portion of the receiving-chute, a finger 52, extending upward from the spring 53, an arm 51, connected to the tilting plate and arranged to bear normally against the finger 52, coin-receptacles e and f, a bridge 26, arranged between said receptacles, slides 27, arranged at the ends of the coin-receptacles, springs, lugs, and locking-bars mounted in 110 connection with said slides, plates 36, carried by the slides and formed with arms 38, which extend over the coin-receptacles, and with cutting-edges 37, arms 40, which extend downward from the arms 38, fingers 8, carried by 115 said arms and extending under the coin-receptacles, and parcel-delivery mechanisms arranged in connection with the slides, substantially as described.

JOSEPH CORBETT.
